UNITED STATES PATENT OFFICE

LEONARD B. NEIGHBOUR, OF MOLINE, ILLINOIS, ASSIGNOR TO DEERE & COMPANY, OF MOLINE, ILLINOIS, A CORPORATION OF ILLINOIS

PORTABLE GRAIN ELEVATOR

Application filed August 11, 1927. Serial No. 212,155.

The present invention relates to portable grain elevators such as are employed for elevating grain into bins, box cars, etc. These elevators usually comprise a vehicle frame 5 or running gear on which is pivotally supported a long elevator tube through which the grain is carried by a flight conveyor. One end of such elevator tube is pivotally connected to the end of the vehicle frame, and 10 when the device is to be placed in operation the other end of the tube is raised to an elevated position, being lowered into proximity to the frame when the device is to be transported. The present invention is 15 primarily concerned with the pivotal mounting of the lower end of the elevator tube on the frame; and with the mounting of the swinging frame or derrick which serves to raise the elevator tube.

20 Referring to the drawings illustrating the invention:

Figure 1 is a fragmentary side elevational view of the elevator, showing the conveying tube thereof raised to its operative position.

25 Figure 2 is a fragmentary elevational view of the rear end of the device.

Figure 3 is a similar view of the front end of the device, the elevator tube being shown in section, and

30 Figure 4 is a fragmentary sectional view illustrating the pivotal mounting of the elevator tube on the running gear.

The machine comprises a main frame 6 which is constructed of two longitudinally extending channel bars 7, and two transversely extending channel bars 8 and 9 at the front and rear ends of the frame respectively. The two longitudinal frame bars 7 are set comparatively close together and extend across the upper sides of the transverse frame bars 8 and 9. The four bars are secured together at their intersections by joining brackets 11. As best shown in Figure 4, each of these joining brackets consists of a plate bent angularly and having its ends twisted upwardly and downwardly to form upper and lower attaching portions for bolting to the frame bars, as indicated at 12.

35 Referring to Figure 2, the rear frame bar 9 constitutes a bolster for the rear axle 13

which extends along the under side of the bar. The ends of the frame bar are rigidly secured to the axle by U-shaped clips 14 extending under the axle and bolted to the frame bar as indicated at 15. Rear wheels 16 55 are suitably journaled on the ends of the axle 13. The front frame bar 8 constitutes an axle for two front steering wheels 17-17. The latter are journaled on spindles 18, having upwardly turned pivot portions 19 which are rotatably supported in upright bearing sleeves or bosses 21. Arms 22 extend inwardly from such bearing sleeves and are bolted to the ends of the frame bar 8, as indicated at 23. Angularly shaped brackets 24 60 are mounted on the inner ends of the spindles and have thrust collars 25 at their upper ends which bear against the under sides of the bearing sleeves 21. Fixedly secured to each of such angle brackets 24, is a forwardly 70 extending arm 26 to which is pivotally connected the outer end of a steering rod 27. The inner ends of these rods overlap and have pivotal connection through a bolt 28 with a tongue supporting member 29. The latter comprises two longitudinally extending angle bars 31 which have their upper flanges bolted to two cross brackets 32-32' located at spaced points along the angle bars 31. The steering rods 27 are pivotally connected to the front bracket member 32, and the rear bracket 32' is pivotally connected to a short bar 33 projecting forwardly from the axle 8 (Figure 1). The two angle bars 31 and the two cross members 32-32' constitute a socket in which a draft tongue or pole is adapted to be detachably held by one or more bolts extending through the vertical flanges of the bars 31. Such socket or mounting member has lateral swinging 80 movement about the axis of its pivotal connection with the stationary supporting bar 33, and in this lateral swinging movement imparts steering movement to the wheels 17-17 through the steering rods 27. As 85 shown in Figure 1, when the machine is set up for operation, the tongue is removed from the socket or supporting member 29 to prevent interference with the elevator tube. The socket or supporting member 29 projects for 90

95 100

wardly to some extent from the axle 8 and beyond the front ends of the longitudinal frame bars 7.

The elevator proper comprises a conveying conduit, which may be of trough or tubular form, the invention having application to either type of elevator. In the construction shown the conveying conduit is of tubular form, being designated 35. This tube is disposed longitudinally of the running gear, which has just been described, and has its inlet end pivotally mounted on the front end of the running gear so that the opposite end of the tube can be raised and lowered between operating and transporting positions. The pivotal mounting of the tube is upon a shaft 36, which also functions as a power transmitting shaft through which power is transmitted to the flight conveyor and to the other power driven devices associated with the conveying mechanism. A belt pulley 37 is mounted on one end of the shaft 36 and is adapted to be belt driven from an internal combustion engine 40 which is located on the rear end of the frame 6. Obviously, any other form of driving mechanism may be employed, such as motion translating devices for utilizing horse power for the operation of the elevator. The other end of the drive shaft 36 carries a sprocket wheel 38 (Figure 3), from which power is transmitted down through a chain to a sprocket wheel mounted on a transversely extending shaft 39. The latter shaft is suitably journaled in a boot 41 which is rigidly secured to the lower end of the elevator tube 35.

Passing upwardly through the tube is an endless flight conveyor constructed of a link chain 42 on which flight disks 43 are mounted at spaced points. The conveyor passes out of the upper discharge end of the conveyor tube and returns down along the upper side of the tube where the chain has guided support on sprocket wheels 44, suitably supported above the tube. The disks 43 have slots in their inner edges to pass over the sprocket wheel or wheels 44. The conveyor passes around a lower sprocket wheel mounted in the boot 41 on the shaft 39, the conveyor being driven by such sprocket wheel. Hingedly connected to the outer end of the boot 41 is a feeding hopper 45. A feeding auger, extending longitudinally within the hopper 45, is driven through any suitable chain drive mechanism 46 which derives its power from the shaft 39.

When the machine is in transport condition, the tube 35 extends approximately horizontally along the running gear. To place the machine in operating condition, the tube is swung upwardly around the pivot axis 36 to the necessary angle for obtaining the desired height of discharge, through the operation of a derrick or lifting frame 48 which is pivotally supported on the rear part of the

running gear. The upper end of such lifting or jack frame carries laterally spaced flanged rollers 49 which track along the underside of the tube 35. The swinging of the lifting frame through its elevating movement is performed by tackle rigging comprising a windlass 51 which is pivotally supported between two laterally spaced vertical standards 52. These standards are suitably secured to the side bars 7 of the frame and are braced in upright position by brace bars 53. A cable 54 passes upwardly from the windlass 51 and through a pulley block 55 which is linked to the upper end of one of the standards 52. From the pulley block 55, the cable passes rearwardly and through a pivot block 56 which is rockably supported in the lifting frame 48, the cable thence extending back to the standard 52, to which the end of the cable is connected as indicated at 57. It will be evident that winding rotation of the windlass 51 will be effective to swing the lifting frame upwardly, thereby elevating the tube 35; and by revolving the windlass in the opposite direction the weight of the tube will be effective to swing the lifting frame rearwardly for permitting the tube to lower. The tube is adapted to be swung down between the spaced standards 52, and projecting forwardly from each of the standards are arms 58 which are adapted to support the free end of the hopper 45, when the latter is swung upwardly over the top of the elevator tube.

Referring to Figure 2, it will be seen that the elevating frame comprises two angle bars 48' which spread laterally from each other in extending down to the running gear. Bolted at 61 to the ends of these angle bars are pivotal mounting extensions 62. These extensions are bent downwardly to lie at the outer ends of the bolster bar 9 and have pivot apertures in their ends which engage over the axle 13 at the ends of the bolster. It will be noted that each pivot extension is laterally confined on the axle in both directions, the hubs 16' of the wheels 16 preventing the pivot extensions from shifting outwardly along the axle, and the U-shaped clips 14 and ends of the bolster 9 preventing the pivot extensions from shifting inwardly along the axle.

I have found that the foregoing construction provides a staunch inexpensive pivotal mounting for the lifting frame. When the conveyor tube 35 is elevated, the upper overhanging end thereof is particularly susceptible to side sway tending to tip or unbalance the machine. These side stresses must be resisted at the points of contact of the wheels 16 with the ground. Any pivotal mounting of the lifting frame on the longitudinal frame bars 7 results in the frame being subjected to the twisting action of such stresses, in transmitting the same to the wheels 16. Moreover, owing to the fact that the frame

bars 7 are usually spaced quite close together, any mounting of the lifting frame directly on such frame bars requires that the lifting frame be constructed as a relatively narrow structure, and brings the two pivot points quite close together, which is also unsatisfactory for supporting the side stresses. I have overcome the foregoing objections by extending the side bars of the lifting frame down directly to the widely spaced wheels 16, which constitute the ultimate points of support serving to carry the side stresses. Thus, the main frame of the vehicle is relieved of all of the side stresses, as well as of the weight of the elevator tube, and the lifting frame is given a pivotal mounting on two widely spaced points of support. Moreover, by utilizing the axle 13 as the pivot bearing for the lifting frame, the expense of a separate bearing or bearings for such frame is avoided.

Another important advantage accruing to this mounting of the lifting frame is that it enables me to place the engine 40 at the rear end of the frame, approximately over the rear axle 13. The comparatively close spacing of the longitudinal frame bars 7—7 is advantageous for permitting full swinging movement of the steering wheels 17. This requires, for stability and economy of construction, that the engine be mounted directly on the frame bars 7, substantially in the central longitudinal plane of the frame, instead of off to one side thereof. Moreover, such central location of the engine permits of a belt drive directly from the belt pulley on the engine shaft to the belt pulley 37 on the drive shaft, thus avoiding the expense of any intermediate counter-shaft. However, such central location of the engine places it directly in the plane of the elevator tube, and in order that the tube shall be capable of being folded down to a relatively low point, for a low over-all height of the machine in transport condition, it is necessary that the engine be moved back to the rear extremity of the frame. In this position its weight is supported directly by the rear axle and its vibration has little effect on the elevator tube.

As above remarked, such location of the engine is made possible by pivotally mounting the side bars 48' of the lifting frame on the rear axle at the widely spaced points shown. This places the lifting frame astraddle of the engine, with the side bars 48' spaced sufficiently far from each side thereof that there is no interference with the swinging movement of the frame.

Referring to Figures 3 and 4, it will be noted that the pivot shaft 36, around which the elevator has its swinging movement, is journaled in two upwardly extending bracket plates 64 which are bolted to the inner sides of the longitudinal frame bars 7. Bearing hubs 65 may be extended laterally from the outer sides of the bracket plates 64 to provide

extended bearing surfaces for the shaft 36; or these bearing hubs may be constructed in the form of a continuous sleeve extending through both of the brackets 64. Pivotally mounted between such brackets, concentrically of the shaft 36, is a tiltable bearing member 66. The upper side of such bearing is formed with an arcuate depression 67 forming a saddle support for the elevator tube 35. The tube is rigidly held in this saddle support by a U-shaped clamping bolt 68, which extends over the upper side of the tube and has its lower ends passing downwardly through flanges 69 projecting from the said bearing, these bolt ends receiving nuts 71 below the flanges.

Referring to Figures 1 and 4, it will be seen that the longitudinal frame bars 7 are extended forwardly beyond the transverse axle bar 8 to provide the overhanging portions 72. It is upon these overhanging portions that the previously described bearing support is mounted, which results in the latter having a considerable overhang beyond the front axle 8. The purpose of this arrangement is to dispose the lower end of the elevator tube—when the tube is inclined upwardly to operating position—considerably forward of the front end of the vehicle. In such position, the lower end of the tube does not interfere with the swinging movement of the tongue supporting member 29. This is desirable because it frequently happens that after the elevator tube has been raised to its operative position, it is necessary to maneuver the vehicle, through actuation of its steering mechanism, in order properly to dispose the discharge end of the tube in the bin or box car. As previously remarked, by virtue of the forward disposal of the pivot axis 36, the lower end of the elevator tube is always held clear of the steering mechanism, permitting actuation thereof at any time for maneuvering the vehicle with the tube in its raised position. It will also be noted that such construction disposes the pivot axis 36 at a relatively low point, so that when the elevator tube is swung downwardly and the feeding hopper 45 is folded over the same, the overhead clearance of the machine will not be appreciably reduced.

Having thus described my invention what I claim as new and desire to secure by Letters Patent of the United States, is:

1. A portable grain elevator comprising a main frame, front and rear axles connected to said frame, said frame comprising a bolster member, to the under-side of which said rear axle is secured, steering wheels pivotally supported on said front axle for lateral swinging movement, wheels on said rear axle spaced outwardly from the sides of said main frame, an elevator tube pivotally supported on said frame in proximity to said front axle, an engine supported on said frame in proximity to said rear axle, means operatively

connecting said engine with the conveyor in said elevator tube, and a vertically swinging lifting frame adapted to raise the discharge end of said elevator tube, said lifting frame comprising side bars extending down on opposite sides of said engine and having pivot portions at their lower ends mounted on said rear axle between the outer ends of said bolster member and the wheels mounted on said axle.

2. In a portable grain elevator, the combination of a main frame comprising two longitudinally extending frame bars, two transversely extending frame bars adjacent to the front and rear ends of said frame, dirigible wheels for the front end of said frame, a rear axle extending under the transversely extending frame bar which is located adjacent to the rear end of said frame, U-shaped clips embracing said axle and securing the same to said latter frame bar, rear wheels on said axle, said longitudinally extending frame bars being disposed between both pairs of wheels and being spaced inwardly therefrom to permit said dirigible wheels to swing freely in steering without striking said longitudinal frame bars, an elevator tube pivotally supported on the front end of said main frame, a lifting frame adapted to raise the discharge end of said elevator tube, said lifting frame comprising two laterally divergent bars, roller means supported at the upper ends of said lifting frame bars for engaging the under-side of said elevator tube, and pivot members secured to the lower ends of said lifting frame bars and engaging on said rear axle between the wheels mounted thereon and said U-shaped clips.

3. In a portable grain elevator, the combination of a frame comprising a rear axle, wheels mounted thereon, a front axle, steering wheels mounted thereon, a steering member projecting forwardly from said front axle and operatively connected with said latter wheels, and elevator tube, and means pivotally supporting said tube on the front end of said frame on a pivot axis disposed above said frame and intermediate the ends of said tube, said pivot axis being located forwardly of the plane of said front axle, whereby to prevent the downwardly swinging front end of said tube which extends forwardly beyond said pivot axis from interfering with actuation of said steering member when said tube is elevated to operating position.

4. In a portable grain elevator, the combination of a frame comprising front and rear axles, wheels on said rear axle, steering wheels on said front axle, steering mechanism projecting forwardly from said axle, an elevator tube adapted to have its rear end tilted upwardly to a discharge position, and means pivotally supporting the

front portion of said tube on said frame on an axis disposed above said frame and forwardly of said front axle to give the front end of the tube an overhang or clearing said steering mechanism when the tube is tilted to operating position.

5. In a portable grain elevator, the combination of a frame comprising two longitudinally extending frame bars, front and rear axles rigidly secured to said frame bars, steering wheels on said front axle, wheels on said rear axle, steering mechanism operatively connected with said steering wheels, an elevator tube adapted to have its rear end tilted upwardly to a discharge position, means pivotally supporting the front portion of said tube on said frame on a pivot axis disposed above said frame and forwardly of said front axle to give the front end of the tube an overhang for clearing said steering mechanism when the tube is tilted to operating position, conveyor mechanism traveling through said tube, an engine mounted on the rear end of said frame operatively connected for driving such conveyor mechanism, and a lifting frame adapted to raise the discharge end of said elevator tube, said lifting frame comprising side bars extending down astraddle of said engine and having bearing support directly on the rear axle in proximity to the rear wheels mounted thereon.

6. In a portable grain elevator, the combination of a frame comprising two longitudinally extending frame bars, front and rear axles rigidly secured to the front and rear portions of said longitudinally extending frame bars, steering wheels, pivot means secured to the outer ends of said front axle and supporting said steering wheels for lateral swinging movement, a steering member projecting forwardly from said front axle and operatively connected with said steering wheels, rear wheels rotating about a fixed axis on said rear axle, said longitudinally extending frame bars being disposed below the tops of said wheels and being spaced inwardly therefrom to permit said steering wheels to swing through a wide range of steering movement without striking said frame bars, a conveyor conduit adapted to have its rear end tilted upwardly to a discharge position, means pivotally supporting the front portion of said conduit on a pivot axis disposed above said frame and intermediate the ends of said conduit, said pivot axis being located forwardly of the plane of said front axle whereby to prevent the downwardly swinging front end of said conduit from interfering with the actuation of said steering member when said conduit is elevated to operating position, said conduit comprising conveyor means, an engine mounted on said frame in overhanging relation beyond said rear axle and operatively connected for driving said conveyor

means, and a lifting frame adapted to raise the discharge end of said conveyor conduit, said lifting frame comprising side bars extending down astraddle of said engine and having bearing support directly on the rear axle in proximity to the rear wheels mounted thereon.
